PLANTER

Jack Duane Forsberg, 1848 Roseland, East Lansing, Mich.

Filed Sept. 26, 1957, Ser. No. 47,881

Term of patent 14 years

(Cl. D35—3)

I claim:

The ornamental design for a planter, as shown.
